UNITED STATES PATENT OFFICE.

THOMAS CHARLES COULL AND WILLIAM ELLISON McLEAN, OF DUNEDIN, NEW ZEALAND.

PAPER-FILE.

1,275,397.

Specification of Letters Patent. Patented Aug. 13, 1918.

Application filed August 21, 1916. Serial No. 116,139.

To all whom it may concern:

Be it known that we, THOMAS CHARLES COULL and WILLIAM ELLISON McLEAN, citizens of the British Empire, residing at the 5 city of Dunedin, in the Dominion of New Zealand, have invented new and useful Improvements in Paper-Files, of which the following is a specification.

This invention relates to paper files and 10 binders for use therewith.

The object of the invention is to provide means whereby some or all of the papers filed on vertical pillars at one side of a plate attached to the back cover of a paper file 15 may be readily removed therefrom and so that a paper or papers may be readily removed from or inserted in the file at any point desired, and whereby also all or a portion or portions of the papers may be bound 20 with covers in book form in the act of being removed from the file without disturbing their position.

The invention is illustrated in the accompanying drawings in which Figure 1 is a 25 perspective view of the invention, Fig. 2 is a perspective view of the invention in operation.

According to this invention there are preferably three pillars 1 with arched tops 2 attached at their lower ends to a horizontal rod 3 hinged to one side of a plate 4 attached to the back cover of the file. The rod 3 has secured to it midway, a hexagonal portion 5 which engages a flat spring 6 secured 35 to the plate 4. The flat spring 6 has a curved extension 7 which is adapted to embrace the hexagonal portion 5 and retard its revolution at the same time permitting the arched pillars to be moved back so as to leave a large 40 space for the binding operation hereinafter described. At the other side of the plate 4 are three vertical pillars 8 and 13, opposite respectively to the pillars with arched ends. The outside pillars 8 are hollow and the central pillar 13 is solid and ends in a pointed hook 10. The middle arched pillar 1 is preferably hollow so that its end 9 may fit on the pointed hook 10. This pillar 1 may be solid with an end shaped to fit the pointed

hook 10. Instead of three pillars there may be two pillars 1, 1 with arched ends 2 coöperating with two corresponding vertical pillars 8. The arched ends of the two outside pillars 1 are adapted to engage the tops of the two opposing hollow pillars 8. The plate 55 and the back cover to which it is secured are perforated with holes in continuation of the two outside hollow pillars.

In operation the known binder cover 11, with adhesive flap similarly perforated is 60 first put on the file resting on top of the back cover and the papers are filed over it. The arched pillars are then pulled over to engage the vertical pillars and any desired papers are thrown over on to the arched pillars which are then pulled open. Papers may then be inserted in or removed from the vertical pillars. The auxiliary known front cover similarly perforated is then put on the file on top of the remaining papers. 65 A cord 12 is then passed up through an outside vertical pillar 8 through the hook 10 of the middle pillar 13 and down the other outside pillar 8. The papers are then together with the binder cover and auxiliary 70 cover in a known manner raised from the file and in that act the hook pulls the cord down through the middle pillar below the binder cover where it is engaged and tied up by the loose ends of the cord in a known 75 manner, thus binding the papers together. The adhesive flap is then secured over all in a known manner.

Having now described our invention we declare that what we claim is:

A paper file, comprising in combination a plate, a pair of hollow pillars rising from said plate, another pillar located midway between said hollow pillars and extending from the plate in the same direction as the 90 outside pillars, a bar pivotally secured to said plate and at a distance from the same, arches secured to said bar and adapted for coöperation with said pillars to close the file, a cam mounted centrally on said bar, 95 one of said arches extending from said cam, a spring mounted on the plate and projecting through the interspace between said bar

and the plate, said spring being provided with a bifurcated extension embracing the cam and in engagement therewith, the two drums of said bifurcated extension being located at opposite sides of one of the arches on said bar.

In testimony whereof we have signed our

names to this specification in the presence of two subscribing witnesses.

THOMAS CHARLES COULL.
WILLIAM ELLISON McLEAN.
